UNITED STATES PATENT OFFICE

BENJAMIN H. CLEM, OF NEW MADISON, OHIO, ASSIGNOR OF FORTY-NINE PER CENT
TO J. A. FLAIG & SON, OF NEW MADISON, OHIO, A FIRM

OSCILLATORY INCUBATOR

Application filed February 25, 1932. Serial No. 595,043.

The object of my present invention, broadly speaking, is the provision of an incubator which is simple in its construction, economical in its operation, absolutely reliable in its results, and which can be manufactured and sold at a comparatively low price.

More specifically stated, by object is to provide an incubator which is adapted to be turned to different degrees of inclination, for the purpose of turning the eggs being incubated therein, that is turning the entire incubator rather than turning individual parts thereof, or turning the eggs individually, or without turning the trays separately, and without opening the incubator.

Another object, in combination with an alternating rotary incubator, is the means for properly conditioning the interior of the incubator, for the purpose of proper incubation, is in providing a relatively stationary unit for automatically maintaining the proper circulation, temperature, and humidity, of the air inside the incubator at all times without the necessity of manual control. Other minor objects and subsidiary advantages and objects of my invention will suggest themselves in the course of the following specification.

One manner of carrying out the principles of my invention, in a practical and efficient construction, is shown in the accompanying three-sheets of drawings, in which—Figure 1 is a front elevation of my incubator, as it appears in vertical operative position. Figure 2 is a cross section of the same, as taken on the line 2—2 of Fig. 1. Figure 3 is a longitudinal section, as taken on the line 3—3 of Fig. 2. Figure 4 is a cross section, as taken on the line 4—4 of Fig. 1. Figure 5 is a detail section, as taken on the line 5—5 of Fig. 1. Figure 6 is a detail section, as taken on the line 6—6 of Fig. 1. Figure 7 is a front elevation, with the doors omitted, showing the interior of the incubator. Figure 8 is an end elevation, indicating the three positions in which the incubator may be operated. Figure 9 is a detail view showing the inner face side of the central door, showing the adjustable ventilator element. Figure 10 is a side elevation of the conditioning unit alone. Figure 11 is an

isometrical view of one of the egg-trays, indicating an egg positioned therein. And Figure 12 is an elevation of the thermostat, and a plan of the wiring.

Similar indices indicate like parts throughout the several views.

In order that the construction, the operation, and the several advantages of my invention may be more fully understood and appreciated, I will now take up a detailed description thereof, in which I will set forth the same as fully and as comprehensively as I may.

My invention is fabricated substantially as follows: The body of the incubator is formed in the nature of a drum, or hollow cylinder, comprising the disc-like end members 1 and 2, which have outwardly projecting door jamb portions 1' and 2', respectively, each having a straight outer forward edge. Said members 1 and 2 are spaced apart, parallel with each other, and they are connected by a plurality of slats 3, or otherwise, which slats are laid adjoining each other, and the upper ends of the members 1' and 2' are connected by a slat 3', and likewise the lower ends of the members are connected by the slat 3''. Secured on the top face of the slat 3' is a beveled strip 4, and likewise secured on the bottom of the slat 3'' is the beveled strip 5.

Thermal insulation of the body of the incubator is provided as follows: The periphery of the body, that is the slats 3, is covered with soft fiber board 6. The fiber board 6 projects laterally whereby it extends evenly with the ends 1 and 2, with its other edges contacting with and being secured under the bevels of the strips 4 and 5. Completely covering the fiber board 6 is a sheet of hard-fiber panel board 7, whose ends are secured under the beveled portions of the strips 4 and 5. The outer faces of the end members 1 and 2, and the projections 1' and 2', are completely covered, each by a sheet of hard fiber board 8 and 9, respectively.

Extending longitudinally and horizontally through the central portion of the body, and projecting outwardly beyond each end thereof, is the axle 10, which is located slightly below the center thereof whereby the

body may tip forwardly, shown in Fig. 8, until the strip 5 engages the sill 15, or it may tip rearwardly until the lug 83 engages the standard 11; or it may be locked in upright position, as in Figs. 2, 3, 4 and 7, by inserting the key 50 through an aperture in the standard 11 and into a corresponding aperture in the member 8. The projecting end portions of the axle 10 provide pivots, which are journaled in the upper portions of the standards 11 and 12, which extend upwardly from the floor A, where they are supported by the foot-members 13 and 14, respectively, which form the supporting base for the incubator. The said standards are of such length as to support the body the desired distance above the floor, whereby the body may be rotated. Said standards are connected by the double member sill 15, which usually rests on the floor line A, however its position, or its equivalent, should be such that it will be engaged by the strip 5, when the body is turned to a certain position, as and for the purpose hereinafter set forth.

25 Said axle may be rotatable or stationary, with relation to the body, as preferred.

The interior of the body is divided into three substantially equal sections, which I will designate, for convenience of description, as the central section, the right-hand section, and the left-hand section, that is when viewed from the front, as in Figs. 1 and 7.

35 Said sections are divided, at the front, by the vertical strips 16 and 17, which are of the same width as the slats 3' and 3'', between which they are secured, and their front edges are flush with the slats 3' and 3'', and are in alignment with the front edges of the jambs 1' and 2', thereby providing the three door openings, as is shown in Fig. 7.

Attached vertically, flat against the inner face of the jamb 1', and extending between the members 3' and 3'', is the strip 18, and 45 a like strip 19 is attached to the jamb 2', and it also extends between the members 3' and 3'', and said strips 18 and 19 are set inwardly forming rabbets for the doors, hereinafter mentioned. Attached vertically against the inner face of the strip 16 is a cleat 20, and a like cleat 21 is attached to the strip 17, and said strips are set inwardly to form rabbets for the door for the central section.

55 Located directly rearward of each of the members 16, 17, 18 and 19, is a vertical post member 22; and midway between each of the members 16, 17, 18 and 19, and its rear post 22, is an intermediate post 23. Attached to each of the members 16, 17, 18 and 19, and to its respective rear and intermediate post 22 and 23, is a wire screen section 24, whose upper and lower edges are substantially even with the top and the bottom of the respective doorways. Extending horizontally and con-

necting the respective members 16, 17, 18 and 19 with their respective rear and intermediate posts 22 and 23, are the respective sets of drawer slides 25, 26, 27 and 28. The drawer slides 25 and 26 are located inside the 70 right-hand section, and the slides 27 and 28 are located in the left-hand section. There are no drawer slides located in the central section. Secured on and extending across between the uppermost slides 25 and 26 is a top plate 29; and likewise secured on and extending across between the uppermost slides 27 and 28 is a top plate 30. The forward end of each of the drawer slides 25 and 28 terminate a short distance inwardly from the front edges of the members 18 and 19; and removably contacting with each set of members 18 and 19 is a vertical locking strip 31 and 32, respectively, and they are easily removable and replaceable. The upper end of each of said strips 31 and 32 is loosely inserted in a socket 33, as shown in Fig. 6, and its lower end portion is prevented from being pushed forwardly by means of a pintle 34.

90 Numeral 35 denotes the drawers or trays of which, in this instance there are six on each side, that is in the end sections. Said trays are adapted to rest slidably on their respective slides 25-26, on one side, and the slides 27-28 on the other side. Formed through each end of each of the trays 35 is a slot 36, whose functions are to provide air passages, for the proper circulation of air there-through, and they also provide hand-holds 100 for the trays. It will now be comprehended that by reason of the interior arrangement of my incubator, I provide means for the free circulation of air entirely around and through the trays. That is to say, the air 105 may move upwardly from the space of the central section to the uppermost part of the body, where it will be deflected thereby to the right and the left, over the top plates 29 and 30, thence downwardly through the 110 spaces between the end members 1 and 2 and the end screens 24, thence into the bottom space below the three sections, except that in passing downwardly, as stated, a certain amount of the air will pass inwardly through 115 the screen sections 24 and be distributed over and through the trays 35, and finally, all of the air will be returned into the central section, and then said operation will be repeated 120 as just described.

125 The door openings, of each of the three sections mentioned, are each adapted to be closed by its respective door, as the respective doors 37, 38 and 39. Each of said doors is formed double, with insulation 40 packed between the front and the back of each door, as indicated in Figs. 5 and 6.

130 The doors 37 and 39 are each provided with a double transparency 41 and 42, respectively, each of which is comparatively narrow,

laterally, but vertically they extend almost the full length of the doors, as shown in Fig. 1, in order that all of the trays may be seen therethrough.

- 5 Formed through the upper portion of the door 38 is an aperture 43, which is adapted to be opened and closed by the slide or shutter 44, shown in Fig. 9, and which is in sliding contact with the back of the door 38, 10 being slidably mounted and guided by the flanged frame 45, and it is manually operable by means of the knob 46, and when in closing position the slide 44 contacts with the stop 47.

The upper forward corner of the shutter 44 15 carries the indicating pointer 48, which acts as a stop when the shutter is opened, that is it contacts with the upper end of the frame 45. Located above the pointer 48 there is a graduated scale 49, for indicating the degree 20 to which the aperture 43 is opened or closed.

The door 37 is mounted to the strip 16 by means of the hinges 74 and 75. The door 38 is mounted to the strip 16 by means of the hinges 76 and 77. And the door 39 is mounted to the strip 17 by means of the hinges 78 and 79.

The door 37 is provided with a spring latch 80. Likewise the door 38 is provided with a spring latch 81. And the door 39 is provided 30 with a spring latch 82.

When the body of my incubator is in upright position as in Fig. 1, and elsewhere in the drawings, it may be locked in that position by means of the key 50, which is inserted 35 through an aperture therefor through the standard 11 and into a corresponding aperture formed through the fiber board 6 and into the member 1. In order to prevent misplacement of the key 50 it is secured to the 40 chain 51, which latter is attached to the eyelet 52 which in turn is secured into the member 11, as shown in Fig. 1.

It is to be observed that when the key 50 is removed, the body of my incubator may be 45 turned forwardly until the strip 5 engages the sill 15; and when the body is turned in the opposite direction the stop lug 83 may engage the standard 11. By this arrangement there are three positions provided for the body of 50 the incubator, all of which are indicated in Fig. 8.

The means for conditioning the interior of my incubator as to heat, humidity and the circulation of air, consists of a single unit 55 suspended upon the axle 10 and located inside the central portion of the incubator, but which is relatively stationary, that is, it does not turn when the main body of the incubator is turned, and it consists, in this instance, 60 of a double frame whose members 53 and 54 are permanently fixed at substantially right-angles to each other, being connected together at their adjoining edges, forming a saddle, which is adapted to stride the axle 10.

65 Permanently fixed and extending upward-

ly from the juncture of said members, 53 and 54, is the comb 55, with a post 56 extending upwardly from the upper edge thereof, whose purpose will hereinafter be made apparent.

The frame member 54 carries a plate 57 70 therein, which plate has a comparatively large aperture B formed therethrough, which extends throughout the major portion of said plate 57.

Located concentrically with the aperture B, 75 and located inwardly from, that is back of, the said aperture B, is an electric motor 58, which is retained in suspension by a plurality of arms 59 which extend from the plate 57. Securely mounted on the outwardly extending 80 shaft of said motor is a fan 60, which is revolvable in or near said aperture B.

Removably mounted in the frame 53 is the water pocket 61, which tapers from its upper end downwardly to its lower edge, that is it 85 expands upwardly, whereby it is formed D-shaped in cross-section. Numeral 62 denotes a clamp by which the pocket 61 is secured in the frame 53, but whereby it may be easily detached therefrom.

Secured across the flat lower edge portion 90 of the inner side of the pocket 61, is the heating element 63, which has the terminal posts 64 and 65, to which are attached the respective wires 66 and 67. Secured to the comb 55, is 95 the socket member 68, which carries the terminal posts 68^a and 68^b, and the said wire 66 is attached to said post 68^a. Attached to the post 68^b is the wire 72, the other end of which is attached to the distributing post 73. 100 The wire 67 is attached to the distributing post 69. Numeral 86 denotes the condenser, which is secured to the comb 55, and extending from the post 69 into the condenser 86, is 105 the wire 87. Also a wire 88 extends from the post 73 into the condenser 86. The purpose of the condenser 86 is only for preventing sparking between the members 71 and 85, and electric current does not flow therethrough. Attached to the post 68^a is the wire 92, which 110 extends to one terminal of the fan motor 58; and attached to the post 68^b is the wire 93, which extends to the other terminal of the motor.

The thermostat, which is mounted on the post 56, comprises a bracket member 94, which is adjustably mounted on said post 56. Integral with the member 94 is the horizontal lower arm 89, having an upturned finger 89' at its outer end. Numeral 90 denotes the intermediate arm, whose outer end is pivoted to the finger 89', and it has an outwardly extending finger 95 which carries the upwardly extending contact 85. Said arm 90 extends inwardly to near the bracket 94, where it terminates in an upwardly extending finger 90'. Pivoted to the upper portion of the bracket 94 is the forwardly extending upper arm 91, which carries, at its forward end, the downwardly extending contact point 71, 130

which is adapted to contact with the point 85. Secured to the central portion of the under edge of the arm 90 are the expansion and contraction discs C and D. Letter E denotes the adjusting screw E, by the manipulation of which any desired degree of temperature may be attained inside the incubator before the heat will be reduced or increased, by the relation of the points 71 and 85 to each other.

19 Returning now to the wiring: Connecting the post 69 and the contact 71 is the wire 70. Connecting the post 73 and the contact 85 is the wire 84. Numeral 96 denotes the connecting plug-head, which is adapted to connect with the plug 68'. Numerals 97 and 98 denote the main line circuit wires, through which electric current is supplied to my invention.

20 The operation of my invention is substantially as follows:

21 First, the doors may be opened and the trays filled with eggs F, resting the filled trays on the slides 25, 26, 27 and 28, as they are shown in Fig. 7. At this time, or at any other time, the pocket 61 should be filled 25 with water. Next the electric current is to be connected, by attaching the head 96 to the plug 68', with said plug inserted in the socket 68, at which time the discs C and D will be spaced apart, with the points 71 and 85 in 29 contact with each other. This last movement will hook up the electric circuit whereby the fan 60, and the heater 63 will be functioning. The doors should now be closed and secured, placing the incubator in the position in which 33 it is shown in Fig. 1. The fan will cause the inside air to circulate around and through all of the trays, at the same time the water in the pocket 61 will become heated, as well as all of the inside air. Proper intake of fresh 39 air, or outlet of impure air, may be had through the adjusting of the slide 44 with relation to the aperture 43, however this need not be changed except at stated periods, indicated by the scale 49, throughout the period 45 of incubation.

46 At certain periods the eggs should be turned, this is accomplished without opening the doors or discontinuing the operation of the fan or the heater, and without touching the eggs, but it is to be accomplished as follows: Assuming, first, that the incubator is turned downwardly to its limit of movement, which will bring the strip 5 into contact with the sill 15, which will be the position of the incubator as indicated by the dotted line G in Fig. 8. Then when it is desired to again turn the eggs one has only to turn the incubator to its limit upwardly, until the lug 83 53 engages the edge of the standard 11, as indicated by the dotted line H in Fig. 8. Turning the incubator from one to the other of said downward and upward limits of movement, will afford the proper turning of the 65 eggs contained therein.

When it is desired to obtain access to the interior of the incubator, one has only to turn it to the position in which it is indicated in solid lines in Fig. 8, that is to say, to the position in which it is shown in Fig. 1, at 70 which position it may be locked by inserting the key 50, as above explained.

It is to be observed that the trays are all secured in position, by means of the removable locking strips 31 and 32, which are adapted to prevent the trays from sliding when the incubator is tipped upwardly or downwardly.

Also it is to be noticed that the conditioning unit, located in the central section, is adapted to adjust itself by gravity, as it is free to turn on the axle 10, but when the device is turned downwardly or upwardly it will not change its position, except relatively 80 to the body of the incubator. However a slight change of the angular inclination of the conditioning unit will be caused by and depending upon the amount of water in the pocket 61, but this is entirely inconsequential.

85 The paramount point to be regulated is the heat inside the incubator, and this is accomplished automatically by the thermostat shown, which acts upon the principle of the dilatation by heat of the compound contacting discs C and D, which warp when the heat attains the desired degree, and the compound dilatation thereof is transmitted to the compound arms 90 and 91, which eventuates in 90 separating the points 71 and 85, and thereby breaking the electric circuit and therefore the heat will be reduced until the desired temperature is restored. And conversely, when the proper temperature is restored the discs C and D will become deflected, thereby 95 permitting the contact 71 to impinge upon the contact 85, thereby restoring the electric circuit and allowing the parts to function as before.

100 It should be understood that the electric circuit which operates the fan 60 is, when the circuit is completed by the insertion of the plug-head 96, direct through the wires 92 and 93, and it is always unvarying when the circuit is plugged in.

105 However the heating element has means for its variation, which I will now make clear: When the contact points 71 and 85 are connected with each other, the circuit through the heater 63 is practically direct and on full 110 maximum power, the same being from the post 68', through the wire 84, the contact 85, to the contact 71, then through the wire 70, to the post 69. From the latter this circuit 115 will continue through the wire 67 to the heating element 63, then returning through the wire 66, to the post 68' of the socket 68, thereby 120 completing the direct full power circuit for the heater 63.

125 Now should the contacts 71 and 85 become separated, by reason of excess heat in the in- 130

cubator, acting upon the discs C and D, then the circuit through the heating element will be disconnected and cease to function, but the fan 60 will continue to operate, by reason of the unbroken circuit through the wires 92 and 93. The condenser 86 is connected to the posts 69 and 73, by the respective wires 87 and 88.

Thermally, humidly, and circulatorily speaking, my incubator is entirely automatic in its operation, as manually it requires only the supplying of water and electricity thereto, and turning the eggs, when required, but only one slight movement of one's hand is required for the latter operation.

It is to be understood that various changes may be made in the several details herein set forth, in the arrangement of the parts, in the details of operation of the parts, without departing from the spirit of the invention or sacrificing any of the advantages thereof which are new and useful and involve invention.

I make no claim per se to the various elements of the conditioning unit, as they are old, and a description thereof would add more to prolixity than to clearness of comprehension.

Having now fully shown and described my invention, what I claim, and desire to secure by Letters Patent of the United States, is—

1. An incubator having a body substantially round in cross section, means for forming the interior of said body into a plurality of intercommunicating sections, a door for closing the entrance to each section, means for removably supporting egg trays in certain of said sections, means provided for the circulation of air through all of said sections and trays, a shaft extending centrally through said body and on which the body is adapted to oscillate, an air conditioning unit located inside said body and suspended from said shaft but not oscillatable with said body, and means for supplying electric current to operate said air conditioning unit.

2. An oscillatory incubator including means for insulating the exterior of the incubator, means for dividing the interior of the incubator into inter-communicating sections, egg trays slidably supported in certain of said sections, an outside door for each section, there being an aperture through the door of the central section for the ingress and egress of air into and from the interior of the incubator, means for controlling the passage of air through said apertures, a fan located in the central section for circulating the air throughout all of the sections, a water container located in the central section, a heater located in the central section, means for sup-

porting the fan, the water container, and the heater so that they will not oscillate with the oscillation of the incubator, and means for operating the fan and the heater by electricity, all substantially as shown and described.

3. An incubator comprising a cylindrical body, a shaft extending horizontally through the body and on which the body may oscillate, said shaft being slightly out of center with relation to the axial center of the body whereby said body will normally assume one of two predetermined positions when it is released, said body being divided into compartments comprising a central compartment and an end compartment on each side of the central compartment, a door leading from outside into each of said compartments, means for removably supporting trays in each of the end compartments, means for circulating air through all of said compartments, an air conditioning unit located in the central compartment, said unit including means whereby said air conditioning unit will remain stationary when the body of the incubator is oscillated, and means for retaining the body in a position other than the predetermined position.

4. In combination, a body adapted to have a limited degree of oscillation, a shaft supporting said body, an air conditioning unit located in the body and carried in suspension by said shaft whereby it is not oscillatable with the body and comprising a saddle loosely engaged on said shaft, an electric motor secured to the saddle, a fan operative by said motor, a water container carried by the saddle, an electric heating element attached to said water container, means for supplying electric current for the operation of said motor and for heating the water, and a thermostat for the automatic control of the electric current.

5. An incubator comprising a body adapted to be oscillated manually, trays for containing eggs located in the body and adapted to be oscillated therewith, there being passageways whereby air may circulate through and around all of said trays, an electrically operable air conditioning unit located in the body, said air conditioning unit comprising an electric motor, a fan operable by said motor, a water containing pocket, a heating element associated with said pocket, means for conducting electric current to operate the motor and for heating the heating element, a thermostat connected into said electric current conducting means, and means for suspending the conditioning unit inside the said body whereby it will not oscillate therewith, all substantially as set forth.

BENJAMIN H. CLEM.
